GROVER LOENING, OF NEW YORK, N. Y., ASSIGNOR TO LOENING AERONAUTICAL
ENGINEERING CORPORATION, A CORPORATION OF NEW YORK

RETRACTABLE LANDING GEAR

Application filed October 27, 1927. Serial No. 229,019.

The present invention relates to retractable or folding landing gears for airplanes, particularly of those of the amphibian, seaplane or flying boat kinds, and is more especially in the nature of an improvement upon the type of structure disclosed in United States Patent No. 1,563,384, granted to me December 1, 1925, though features of the invention are not confined for their application to a single plan of construction.

The general and specific objects of the invention and the advantages to be derived from its use will appear more fully as the following description of a preferred form proceeds, and the invention will be particularly pointed out in the appended claims.

In the drawings:

Fig. 1 is an elevation, partly in section and with certain elements omitted, of a portion 20 of an amphibian hull equipped with a landing gear constructed in accordance with the invention, the gear being in extended position;

Fig. 2 is a transverse section, parts being 25 broken away, of the structure shown in Fig. 1; and

Fig. 3 is a view similar to Fig. 2, on a larger scale and showing the landing gear in its retracted position. The body of the machine comprises an upper portion 1 and a lower or hull portion 2, preferably constructed as a unit, and provided with transverse bulkheads 3 and 4 forming walls of a compartment 5 open at opposite sides of the hull 35 and separated from the buoyant sections thereof. In the sides of the hull, intersecting the space 5, are wheel pockets 8 for receiving the landing wheels 10 when the latter are in their retracted positions.

The landing gear includes a pair of triangular wheel-carrying frames pivoted to the chine regions at opposite sides of the hull, and as they are of identical form the following description of one of said frames 45 will suffice.

The frame comprises a member 11 forming an axle at its outer end carrying the wheel 10, and pivoted at its inner end to the bracket 12, at the end of a transverse brace 50 13. Spaced twin struts 14 are secured at

one end to a collar or yoke 15 secured to the member 11 adjacent the hub of the wheel, and are braced longitudinally of the hull by webs 14^a and cross piece 17. At their upper ends, the struts 14 are joined to struts 16 55 which extend inwardly to the pivot upon which the member 11 is mounted. Secondary bracing struts 18 join intermediate portions of the struts 14 with the pivot for the frame. From Figs. 1 and 2 it will be obvious that the construction just described provides a rigid but light triangular or pyramidal frame of considerable width fore and aft, the wheel being carried at the lower outer corner of the frame, and the upper 60 outer corner being utilized in a manner which will be described, unusual structural strength to resist the various stresses encountered being obtained. In order to further strengthen the structure against such strains, 65 a rod 19 extends between the pivot point of the frame and an anchoring bracket 19^a secured to the hull in a forwardly located position, and an additional diagonal bracing member comprising longitudinal members 70 20, 20^a and cross struts 20^b, 20^c, is pivoted at one end to the bracket 19^a and secured 75 at its opposite end to the yoke 15.

A rocker-arm 21 forming an important element of the invention, is pivoted at the 80 apex or upper outer corner of the triangle formed by the juncture of the struts 14 and 16, this member being preferably in the form of a bell-crank having a short arm extending outside the triangular frame, to which is 85 pivoted the outer end of the actuating link or translatable strut 22, and a long arm extending within the triangular frame. The end of the crank arm within the frame is formed to receive the strands of an elastic 90 shock-absorbing cable 23 looped about the cross-piece 17.

Referring now to Fig. 2, it will be seen that the rigid pivotal wheel-carrying frames, when in extended position, are resiliently sustained through the medium of the shock-absorbing elements 23 and the rocker-arms 21, the latter rocking at one point on the frames and fulcrumed at another point on the actuating links 22. The upward thrust 100

on the wheels caused by landing shocks swings the frames about the pivots 12^a, this action in turn swinging the long arms of the bell cranks 21 inward and upward. Motion of the bell cranks in this direction is resisted by the elastic cables 23, which serve to absorb the landing shocks unless the latter are unusually severe, in which case the arms of the bell cranks may be moved in until their further motion is arrested by contact with stirrups 24 attached to the members 11 and 16.

The mechanism for extending and retracting the wheel frames is guided on a pair of reversely disposed diagonal slide rods 25, secured at their lower ends in suitable sockets 26 attached to the bottom of the hull, and at their upper ends secured in anchor blocks 27 braced against the transverse structural member 27^a. Plain slide rods have advantages over screws in cost of producing and principally because they are not likely to become injured or incapacitated in the rough usage to which these landing gears are subjected. Furthermore, they lend themselves to quick and very easy operation by simple manual means employing cables.

Sliding traveler blocks 28 are mounted on each of the rods 25 and have pivoted thereto the inner ends of the links 22, the outer ends of which are pivoted to the short arms of the rockers 21. The position and movement of the blocks 28 is controlled by cables 29 and 30, the former passing over pulleys 31 and 32 to drums 33 and the latter over pulleys 34 and 35 to the same drums, the cables 29 and 30 however being wound on the drums in opposite directions. The drums 33 are mounted on a common shaft 36 secured to the upper portion 1 of the hull and this shaft carries a driven sprocket 37 connected by a chain 38 with a drive sprocket 39 mounted in a position easily reached by the pilot and actuated by a crank handle 40. The sprocket 39 is formed with a ratchet wheel 41 adapted to be engaged by either jaw of a reversible double pawl 42, the position of which is controlled by a hand lever 43 and spring 44. This reversible device permits of operation of the cable operating means in one direction only, in one position of the device, and in the opposite direction only when the device is in the other position.

From the figures and the foregoing description the action of the mechanism in extending and retracting the wheels and frames will be largely obvious, rotation by the pilot of the operating handle 40 acting through the driving mechanism to slide blocks 28 along the rods 25 to the upper or lower ends of the latter, as the case may be, and through the medium of rods 22, swinging the wheel frames about their pivots 12^a to their extended or retracted positions.

When the wheel frames are in use in ex-

tended position, they are held against retraction by links 22 acting as thrust members. The combined weight of the wheels and frames is substantial, and in order to aid in moving them both from the fully extended and fully retracted positions, and to yieldingly resist their movement in both directions past a position of equilibrium, elastic cables 45 are provided, each of which is in the form of a closed loop passing through an eye 46 at the outer end of one of the links 22 and over the pulleys 47 and 48 secured to the member 27^a. In the position shown in Fig. 2 the cables 45 are in tension and their tendency is to swing the wheel frames about the pivots 12^a, thus counterbalancing a substantial amount of the weight of the wheels and frames and aiding in lifting the wheel frames toward their retracted position. As the frames are moved toward the fully retracted position shown in Fig. 3, the cables 45 move to a position such that one leg of each triangular loop intersects a wheel pocket and lies in the path of the wheel, thereby forming a resilient check against which the wheel strikes as it moves toward its fully retracted position. The wheels, when fully retracted, stretch the cables in a manner clearly shown in the figure, so that with the gear in this position the cables are again in tension, the resulting force aiding in moving the wheels out of their pockets when it is desired to extend the gear. The elastic cables also act frictionally and tensionally to keep the wheels from spinning when the plane is in motion with the landing gear folded. When the landing gear is extended these elastic cables act first to aid in starting the wheels and frames, which are then folded inwardly of the vertical center lines, and later when the force of gravity acts with the motion they act to counterbalance in a substantial measure this added force. An important function of the cables is to equalize, or approximately equalize, the effort required of the operator in folding and extending the gear. In this connection the buoyant effect of the wheels in water is also to be taken into consideration in determining the tension to be put into the cables.

Many changes and modifications in the precise form of the preferred embodiment hereinbefore described may be made without departing from the scope of the invention. While the landing gear has been shown applied to a boat or central flotation body, it will be evident that by appropriate minor modification the two halves of the gear may be applied to laterally spaced floats of seaplanes.

I claim:

1. In a landing gear, a wheel carrying frame mounted to swing between an extended and a retracted position, a link serving to hold the frame in extended position, a mem-

- ber rockingly connected to the frame and also to the link, and shock-absorbing means between said member and the frame.
2. In a landing gear, a wheel carrying frame mounted to swing between an extended and a retracted position, a link serving to hold the frame in extended position, a member rockingly connected to the frame and also to the link, and shock-absorbing means connected to the rocker member.
3. In a landing gear, a triangular wheel carrying frame mounted to swing between an extended and a retracted position, a link serving to hold the frame in extended position, a rocker member at the apex of the triangle and pivotally connected at another point with the link, and shock-absorbing means connected to the rocker member.
4. In a landing gear, a wheel carrying frame mounted to swing between an extended and a retracted position, a link serving to hold the frame in an extended position, a crank rockable on the frame and having a long arm and a short arm, the latter pivoted to the link, and shock absorbing means between the long arm and the frame.
5. In a landing gear, a wheel carrying frame mounted to swing between an extended and a retracted position, a link serving to hold the frame in extended position, a member rockingly connected to the frame and also to the link, shock absorbing means connected to the rocker member, and means on the frame for limiting the movement of said rocker member.
6. In a landing gear, a pivoted member mounted at one end, spaced pairs of struts secured to said member to form a double triangular framework, a crank pivoted between said spaced struts at the apex of the triangle, said crank comprising an arm extending from the pivot inwardly of the triangular frame, and an arm extending in another direction, an elastic cable secured to said first-mentioned arm and to the frame and resisting rotation in one direction of the crank about its pivot, and a link pivotally secured to said last-mentioned arm to hold the frame in a relatively fixed position.
7. A retractable landing gear comprising wheel-carrying frames movable past a point of equilibrium between retracted and extended positions, and resilient means operatively associated with the frames to counterbalance it as it approaches both extended and retracted positions.
8. In an amphibian plane, a float having a pocket, a landing wheel, a pivoted frame carrying said wheel and arranged to swing it downwardly to a retracted position in the pocket, means for swinging the frame to retracted position, and an elastic cable connected with the frame and the float and arranged to yieldingly resist the movement of the wheel to retracted position in the pocket.
9. In an amphibian machine, the combination with a retractable landing gear comprising pivoted wheel-carrying frames and means for swinging the frames between extended and retracted positions, of elastic cables operatively connected to the frames and to spaced fixed points on the machine to form closed loops, said loops exerting a counterbalancing lifting force on the wheels and frames in both the extended and retracted positions.
10. In an amphibian machine, and in combination with a retractable wheeled landing gear and means for operating the same, means for elastically counterbalancing the weight of the gear, said counterbalancing means being so disposed as to press against the wheels in the retracted position to keep them from spinning.
11. The combination with a retractable landing gear and cable means for operating the same, a handle for operating said cables, a ratchet wheel, and a reversible pawl cooperating with said ratchet wheel to permit the handle to be turned in one direction only in one of its positions, and in the reverse direction only when it is in the other of its positions, a handle for shifting said pawl, and a resilient operating connection between said pawl and said handle.
